(57) CLAIM

The ornamental design for a combined armless chair with storage compartment, as shown and described.

DESCRIPTION

FIG. 1 is a top, front, left perspective view of a combined armless chair with storage compartment;

FIG. 2 is a top, front, left perspective view thereof;

FIG. 3 is a front elevational view thereof;

FIG. 4 is a rear plan view thereof;

FIG. 5 is a left side view thereof;

FIG. 6 is a right side view thereof;

FIG. 7 is a top view thereof;

FIG. 8 is a rear plan view thereof;

FIG. 9 is a front perspective view of FIG. 1 identical to FIG. 2, shown in a first alternate condition of use;

FIG. 10 is a front perspective view thereof shown in a second alternate condition of use;

FIG. 11 is a front perspective view, shown in a third alternate condition of use;

FIG. 12 is a left side elevational view, shown in a first alternate condition of use;

FIG. 13 is a left side elevational view, shown in a second alternate condition of use;

FIG. 14 is a left side elevational view, shown in a third alternate condition of use;

FIG. 15 is a top, rear, left perspective view, shown in a closed configuration;

FIG. 16 is a top, rear, left perspective view, as shown in FIG. 12 in a first alternate condition of use;

FIG. 17 is a top, rear, left perspective view, as shown in FIG. 13 in a second alternate condition of use; and,

FIG. 18 is a top, rear, left perspective view, shown in a third alternate condition of use.

The curved broken lines on the combined armless chair with storage compartment illustrate unclaimed contours of the cushions.

The broken lines illustrating the feet or base supports form no part of the claimed design.

The broken lines in FIG. 1 indicating additional seats are for environmental purposes and form no part of the claimed design.
